WHEEL COVER

Robert W. Ryerson, Chicago, Ill.

Application October 3, 1952, Serial No. 21,677

Term of patent 14 years

(Cl. D14—30)

To all whom it may concern:

Be it known that I, Robert W. Ryerson, a citizen of the United States, residing at Chicago, in the county of Cook, State of Illinois, have invented a new, original, and ornamental Design for a Wheel Cover, of which the following is a specification, reference being had to the accompanying drawing, forming a part thereof.

Figure 1 is a cross-sectional view of the wheel cover showing my new design taken along the line 1—1 in Figure 2, and

Figure 2 is a front view of the wheel cover.

The dotted lines on the drawing are for illustrative purposes only.

I claim:

The ornamental design for a wheel cover, substantially as shown and described.

ROBERT W. RYERSON.
